UNITED STATES PATENT OFFICE.

SAMUEL W. HUDSON, OF HUDSONDALE, PENNSYLVANIA.

STEAM-MOTOR.

SPECIFICATION forming part of Letters Patent No. 249,527, dated November 15, 1881.
Application filed August 25, 1881. (No model.)

To all whom it may concern:

Be it known that I, SAMUEL W. HUDSON, of Hudsondale, Carbon county, Pennsylvania, have invented certain new and useful Improvements in Steam-Motors, of which the following is a specification, reference being had to the accompanying drawing, which is a vertical central section through my apparatus.

My invention consists in certain improvements, hereinafter to be designated, in steam-engines of the class which operate continuously in one direction by means of the pressure of steam upon a series of piston-heads carried by an endless chain.

15 The cylinders A B are connected at the top by the dome or chamber C, and their lower ends are submerged in the water-tank D. An endless chain, E, passes through the cylinders and over pulleys c and d, mounted respectively in the chamber C and tank D, and carries any suitable number of piston-heads e. These piston-heads snugly fit the smaller portions of the cylinders A B as an ordinary reciprocating piston fits its cylinder. A pipe, F, connects with the smaller portions of the cylinders by openings f f'. By means of a cock, G, either one of the cylinders may be thrown into communication with the pipe F and the other one cut off, as shown in the drawing. A similar cock, H, controls the openings h h', which connect the cylinder with the pipe I just at the top of the enlarged portions of the cylinders. J K are exhaust-valves placed above the openings f f'.

35 The operation of the apparatus is as follows: When steam is admitted from the pipe I into the cylinder B it will drive the pistons with a continuous motion up the cylinder. As the pistons move up and around, the steam will exhaust through the valves J and K. At the opening f a jet of cold water is admitted from the pipe F, and makes the vacuum more perfect by condensing any steam which may be carried thus far by the piston-heads. The exhaust-valve J might be dispensed with and the

cold water relied upon to condense the steam. Thus it will be seen that the piston-heads will be continuously driven in one direction by the steam, and that the power of the steam will be assisted or supplemented by the vacuum in the opposite cylinder. A head of water sufficient to act by its weight on the piston-heads might be admitted at f, and thus still further increase the power of the machine. The head of water would, however, have to be carefully regulated, in order not to crowd or back up in the cylinder and interfere with the movement of the pistons. The movement of the machine may be reversed by reversing the positions of the cocks G and H. The power of the machine can be applied from the shaft of the sprocket e by suitable gearing. The pressure of the steam will force the level of the water in the cylinder B down, while the vacuum in the cylinder A will cause the water to rise therein. The cylinders will therefore have to be submerged to a depth to suit the pressure of the steam, so that the water will not be blown out of the cylinder B or rise too high in A, as will be well understood.

Having thus described my invention, what I claim is—

1. The combination of the partly-submerged cylinders A and B, having the exhaust-valves J and K and steam-inlet h', the sprockets, chain, and piston-heads, substantially as set forth.

2. The combination of the partly-submerged cylinders A and B, the exhaust-valves J and K, the sprockets, chain, and piston-heads, the steam inlet or inlets, their controlling-cock, the water inlet or inlets, and their controlling-cock, substantially as set forth.

In testimony whereof I have hereunto subscribed my name.

SAMUEL W. HUDSON.
